TEMPERATURE REGULATOR

Fritz Frederick Uehling, Passaic, N. J.

Application March 9, 1935, Serial No. 10,343

20 Claims. (Cl. 175—320)

This invention relates to means for regulating high temperatures in connection with which temperatures a thermo-couple is utilized to provide an electro-motive force, the variations in which 5 force actuate the controlling elements. More particularly the invention provides a novel form of galvanometer or thermo-couple actuated means which in combination with novel circuits and relays increases or decreases the heat input to 10 a furnace or any other chamber or medium, the temperature of which is to be regulated.

Although the following description and accompanying illustrations cover a particular application of the invention for regulating temperature, 15 it is obvious from the disclosures that the invention may be utilized to regulate any variable so long as the variable produces an electro-motive force which varies in proportions to changes in the variable regulated.

Figure 1 is a diagrammatic illustration partly 20 in cross-section, which shows a novel form of galvanometer with its relays and all the important elements of the invention; Figure 2 is a cross-section through the galvanometer; Figure 3 is an 25 other view of the relays with the positions of their switches opposite to that illustrated in Figure 1.

The moving element of the galvanometer consists of a pendulum 12, Figure 1, which is pivoted at 16 and 17, Figure 2. To the lower end of the 30 pendulum and at right angles to its axis is fastened a permanent magnet 5 as illustrated. The pendulum which includes the permanent magnet is supported by and pivoted on two cross pieces 14 and 15 which are fastened at the upper end 35 of a frame 13 from which they are electrically insulated. Two solenoids 3 and 4 are fastened to the lower end of the frame, one on each side of the permanent magnet as illustrated, with their elevation such that their axes coincide with the 40 axis of the magnet. The solenoids are connected in series, and are wound so that when energized by an electric flow in one direction, the pendulum which includes the permanent magnet will be forced to the right and when energized by an 45 electric flow in the opposite direction, the pendulum will be forced to the left. The advantage of this novel form of galvanometer lies in the fact that the actuating coils are stationary and may therefore be wound for any number of am- 50 pere turns regardless of the quantity or weight of the wire required, without in any way affecting the mass of the movable member. Furthermore the pendulum can be made very light and therefore very responsive to magnetic changes 55 while the sensitivity may be increased almost in-

definitely by merely increasing the length of the arm 12. Such an electrically influenced pendulum is particularly well suited for the purpose here-with described because as will be presently shown, its extreme motion need never exceed more than 5 several thousandths of an inch, thereby insuring responsive action to the slightest flow of electric current through the solenoids.

The initial reaction between the magnet 5 and the solenoids 3 and 4 is caused by the electro- 10 motive force of a thermo-couple 21. The circuit which includes the couple and the solenoids is illustrated by dotted lines to distinguish it from the other circuits. This circuit starts at the couple 21, thence through wire 22 to solenoid 4, 15 from solenoid 4 through wire 19 to solenoid 3, from solenoid 3 through wire 20, to an adjustable potentiometer 14—78, and thence through wire 73 back to the couple. The purpose of the potentiometer 14—78 will be presently described. 20

The magnet 5, Figure 1, is provided with a silver contact piece 8 at one end, and a similar contact piece 9 at its opposite end. Electrical contact is respectively established between these contact pieces and contact screws 6 or 7 depending upon 25 whether the pendulum is deflected to the left or to the right. The contact screws are electrically insulated by means of insulation pieces 11 and 10 respectively, and are adjustable so that the gap between the screws and their respective contact 30 pieces can be made as small as desired. Electric contact thus established between the pendulum and one or the other of the screws 6 and 7 closes the proper circuits to actuate the relays A, B, and C in the manner and for the purpose to be 35 presently stated.

The relay or coil A when energized actuates an armature 55 which is pivoted at 51. When the coil is deenergized, the armature is held in its normal position as illustrated, by a contact spring 40 42 through an insulation piece 58 which communicates with an extension arm 56. A contact blade 41 is so placed with respect to the contact spring 42 that when the coil A is energized, electric contact will be established between them. 45 The contact spring 42 and the contact blade 41 will hereinafter be referred to as switch 41—42, said switch being closed when the coil A is energized and open when said coil is deenergized.

Similarly the relay or coil C when energized 50 actuates an armature 51 which is pivoted at 53. When the coil C is deenergized the armature is held in its normal position as illustrated, by means of a contact spring 46 through an insulation piece 54 which communicates with an extension arm 55

52. A contact blade 47 is so placed with respect to the contact spring 46 that when the coil C is deenergized, electrical contact will be established between them. The contact spring 46 and the contact blade 47 will hereinafter be referred to as switch 46—47, said switch being open when the coil C is energized and closed when said coil is deenergized.

10 The relay or coil B when energized actuates an armature 59 which is pivoted at 61. This armature communicates with a number of switches through its arm 60 and insulation pieces 62, 63 and 64. When the coil B is deenergized the armature 59 is held in its normal position as illustrated in Figure 1, by means of three contact springs 49, 37 and 70. Contact blades 29, 38 and 69 are so placed with respect to contact springs 49, 37 and 70 respectively that when the coil B is energized, electric contact will be established between 49 and 29, 37 and 38, and between 70 and 69. Another contact blade 30 is provided which makes electric contact with blade 29 when the coil B is deenergized and with which it breaks contact when said coil is energized. The contact blade 29 is designed as illustrated to permit making contact between 49 and 29 before contact between 29 and 30 is broken. The contact spring 49 and the contact blade 29, the contact blade 29 and the contact blade 30, the contact spring 37 and the contact blade 38, and the contact spring 70 and the contact blade 69, will hereinafter be referred to as switches 29—49, 29—30, 37—38, and 69—70 respectively. Switches 29—49, 37—38 and 69—70 will thus be open and switch 29—30 closed when the coil B is deenergized as illustrated in Figure 1, and when the coil B is energized, switches 29—49, 37—38 and 69—70 will be closed and switch 29—30 open as illustrated in Figure 3. The coils A, B and C and the described switches are supported by an insulation piece 65 which insulates the terminals of the coils as well as all of the elements of the switches as illustrated.

45 The circuit which is closed by electrical contact between the pendulum and contact screw 7, starts at battery 26, thence through wires 25 and 23 to solenoid 3, from solenoid 3 through wire 19 to solenoid 4, from solenoid 4 through wires 24 and 33 to the pendulum support 14, and from 50 the pendulum support through a flexible connection 18 to the pendulum arm 12. When the pendulum is deflected to the right so that contact is established between the contact piece 9 and the screw 7, the circuit will be closed and continues 55 through wire 32 to the coil A, and thence through wire 31, switch 29—30 and wires 28 and 27 back to the battery, the switch 29—30 being closed when the coil B is deenergized as illustrated in Figure 1. Similarly the circuit which is closed 60 by electrical contact between the pendulum and the contact screw 6, starts at battery 12, thence through wires 25 and 23 to solenoid 3, from solenoid 3 through wire 19 to solenoid 4, from solenoid 4 through wires 24 and 33 to the pendulum support 14, and from the support through the flexible connection 18 to the pendulum arm 12. When 65 the pendulum is deflected to the left so that contact is established between the contact piece 8 and the screw 6, the circuit will be closed and continues through wire 39 to the switch 37—38, and when the switch 37—38 is closed by the coil B, as illustrated in Figure 3, the circuit continues through wire 36, coil C and wires 35 and 34 back to the battery.

75 There are two circuits which include the coil

B, the first of which includes the switch 30—29, and the second or holding circuit which includes switch 29—49. The first of said circuits starts at battery 12, thence through wires 34 and 48 to switch 46—47, from said switch through wire 45 to the coil B, from the coil B through wires 44 and 43 to switch 41—42 and from the switch 41—42 through wires 40 and 27, and thence through battery 26 back to battery 12. Similarly the second or holding circuit through the coil B starts at battery 12, thence through wires 34 and 48 to switch 46—47, from said switch through wire 45 to the coil B, from coil B through wires 44 and 50 to switch 29—49, which switch is closed when the coil B is energized as illustrated in Figure 3, and from switch 29—49 through wires 28, 27 and battery 26 back to battery 12. It will be noted that both of the circuits which include the coil B include the batteries 26 and 12 in series.

20 Let us now assume that the current flowing through the thermo-couple circuit is of the proper polarity and just sufficient to cause a very delicate contact between the contact piece 9 and the contact screw 7. As previously stated, the circuit which is closed by this contact includes the coil A, the switch 29—30, the battery 26 and the solenoids 3 and 4. The delicate pressure which the contact piece 9 exerts against the screw 7 by virtue of the thermo-couple circuit is 25 however so small that the contact resistance will not permit sufficient current to flow through the circuit from battery 26 to actuate the armature 55. The battery 26 is however of the proper polarity so that the current which does flow through the circuit will cause the solenoids to react with the permanent magnet 5 to force the contact piece 9 tighter against the screw 7. The increased pressure between the contact piece 9 and the screw 7 will obviously decrease the contact resistance thereby increasing the flow through the circuit which in turn still further increases the pressure between the contact piece 9 and the screw 7 to again increase the flow. It therefore follows that regardless of the delicacy 30 of the initial pressure of the contact piece 9 against the contact screw 7 as caused by the thermo-couple circuit, said pressure will build up almost instantaneously until sufficient current flows from the battery 26 to actuate the armature 55. The armature 55 will thus react with the coil A to close the switch 41—42 immediately after the small flow through the thermo-couple circuit causes the initial contact between the contact piece 9 and the contact screw 7. The closing of the switch 41—42 will close the first 35 circuit (already traced) through the coil B which coil when energized, reacts with the armature 59, Figure 3, to close the switches 29—49, 37—38 and 69—70, and to open the switch 29—30. The switch 29—30 thus opens the circuit through the coil A which circuit was initially closed by contact between 7 and 9, thereby permitting the switch 41—42 to open, and simultaneously closing the switch 29—49 to close the second circuit 40 (already traced) through the coil B. This second or holding circuit through the coil B maintains the switches in the position illustrated in Figure 3. The circuit which includes the battery 26, the switch 29—30, the coil A and the solenoids 3 and 4 is now open through the switch 29—30 thus again permitting the pendulum to be influenced solely by the current flowing through the thermo-couple circuit.

45 Now let us assume that the flow through the 50

thermo-couple circuit has changed so that the pendulum is deflected to the left just sufficiently to cause a very delicate contact between the contact piece 8 and the contact screw 6. As previously stated the circuit which is closed by contact piece 8 and the screw 6 includes the switch 37-38, the coil C, the battery 72 and the solenoids 3 and 4. The delicate pressure which the contact piece 8 exerts against the screw 6 by virtue of the thermo-couple circuit is however so small that the contact resistance will not permit sufficient current to flow through the circuit from battery 72 to actuate the armature 51. The battery 72 is however of such polarity (opposite to that of battery 26) so that the current which does flow through the circuit will cause the solenoids to react with the permanent magnet 5 to force the contact piece 8 tighter against the screw 6. The increased pressure between the contact piece 8 and the contact screw 6 will obviously decrease the contact resistance thereby increasing the flow through the circuit which increased flow in turn still further increases the pressure between the contact piece 8 and the screw 6 to again increase the flow. It therefore follows that regardless of the delicacy of the initial pressure of the contact piece 8 and the contact screw 6 as caused by the thermo-couple circuit, said pressure will build up almost immediately until sufficient current flows from the battery 72 to actuate the armature 51. The armature will thus react with the coil C to open the switch 46-47 immediately after the small flow through the thermo-couple circuit has caused the pendulum to deflect just sufficiently to the left to cause a very delicate contact between the contact piece 8 and the screw 6. As previously stated, the circuit which includes the switch 46-47 is the second or holding circuit through the coil B. The opening of the switch 46-47 as caused by contact between 6 and 8, will therefore release the armature 59 thus permitting the switches actuated thereby to return to the positions illustrated in Figure 1. The switch 37-38 being now open, the flow from battery 72 through the solenoids 3 and 4 and coil C will discontinue, thus permitting the pendulum to again be influenced solely by the current flowing through the thermo-couple circuit and allowing the armature 51 to return to its normal position to again close the switch 46-47.

It thus follows that regardless of the delicacy of the force which the pendulum may exert against the contact screw 7, the slightest contact between said screw and the contact piece 9 will, in the manner stated, cause the switches 29-49, 29-30, 37-38 and 69-70 to assume the positions illustrated in Figure 3. In this position the switch 29-49 closes the previously traced holding circuit through the coil B which maintains the switches in that position. The opening of switch 29-30 breaks the previously traced circuit which includes the battery 26, the coil A, the contact screw 7 and the solenoids 3 and 4, thus preventing any further influence from the battery 26 on the pendulum and at the same time deenergizing the coil A to again cause the opening of switch 41-42 which switch was temporarily closed to cause the initial energizing of the coil B. The closing of switch 37-38 closes a gap in the circuit which includes the coil C, the battery 72, the solenoids 3 and 4 and the contact screw 6, and which circuit, in the manner previously stated, may now be closed by contact between 6 and 8. The switch 69-70 in the position

illustrated in Figure 3 closes a circuit to energize a furnace 66. This circuit starts at battery 61, thence through wire 68 to the switch 69-70, from the switch to the furnace and thence back to the battery.

Similarly the slightest contact between the contact screw 6 and the contact piece 8 will, in the manner already stated, cause the switches 29-49, 29-30, 37-38 and 69-70 to assume the positions illustrated in Figure 1. These positions, as previously stated, are caused by breaking the holding circuit through B when the switch 46-47 is opened by the coil C. The opening of switch 37-38, Figure 1, breaks the previously traced circuit which includes the battery 72, the coil B, the contact screw 6 and solenoids 3 and 4, thus preventing any further influence from the battery 72 on the pendulum and at the same time deenergizing the coil C to again close the switch 46-47 which switch was temporarily opened to break the holding circuit through coil B to permit the switch to assume the positions illustrated in Figure 1. The closing of switch 29-30 closes a gap in the circuit which includes the coil A, the battery 26, the solenoids 3 and 4, and the contact screw 7 so that this circuit, in the manner already stated, may now again be closed by contact between 7 and 9. The switch 69-70 in the position illustrated in Figure 1 opens the circuit through the furnace.

The energizing circuit through the potentiometer wire 74 includes a battery 76 and a resistance R. It is therefore obvious that the brush 78 may be adjusted so that the drop across the potentiometer will exactly balance the electro-motive force from the couple 21 for any given temperature of the furnace. Let us assume for example that the potentiometer is adjusted for a furnace temperature of 1000° F. and that the furnace is at that temperature. Under these conditions there will obviously be no current flowing through the thermo-couple circuit, there will be no reaction between the pendulum and the solenoids 3 and 4, and the pendulum will assume its null position as illustrated. The solenoids 3 and 4 are so wound that if the temperature of the furnace exceeds the temperature for which the potentiometer is set, the flow through the solenoids will be in the proper direction to cause the pendulum to deflect to the left thus establishing contact between 6 and 8 which, in the manner already stated, causes the switches to assume the positions illustrated in Figure 1, in which position the switch 69-70 will be open to deenergize the furnace. Although the contact piece 8 may, for a time, continue to touch the contact screw 6, the circuit through the solenoids from the battery 72 will, in the manner stated, be broken through the switch 37-38, thus permitting the pendulum to move to the right as the furnace cools. When the furnace has cooled below the temperature for which the potentiometer is set, then the electro-motive force of the potentiometer will be greater than that of the couple and the current through the couple circuit will flow in the proper direction to cause the pendulum to deflect to the right, thus establishing contact between 7 and 9 which, in the manner stated, will cause the switches to assume the positions illustrated in Figure 3, in which position the switch 69-70 will be closed to energize the furnace. Although the contact piece 8 may, for a time, continue to touch the contact screw 7, the circuit through the solenoids from the battery 26 will, in the manner stated, be broken through

the switch 29—30, thus permitting the pendulum to move to the left as the furnace temperature increases.

The brush 78 of the potentiometer may of course be set for any desired furnace temperature. When the temperature of the couple exceeds that for which the potentiometer is set, the slightest flow of current through the couple circuit will, in the manner stated, cause the switches to assume the positions illustrated in Figure 1, thereby opening the furnace circuit to lower the temperature, and when the temperature of the couple drops below that for which the potentiometer is set, then the slightest flow of current through the couple circuit will, in the manner stated, cause the switches to assume the positions illustrated in Figure 3, thereby closing the furnace circuit to increase the temperature. The regulator may therefore be actuated to maintain any desired temperature in the furnace depending upon the position to which the brush of the potentiometer is set.

Although I have illustrated the moving element of the galvanometer in the form of a pendulum, the center of gravity of which is directly below the line on which it is pivoted, it is obvious, without in any way departing from the invention, that even more delicate effects may be obtained by pivoting the moving element of the galvanometer on a line at a slight angle to the vertical thus permitting a swinging movement of the movable element in a plane at a slight angle to the horizontal. The effect of such an arrangement would be similar to that produced on a garden gate when the axis of the hinges is slightly tilted, thus permitting the gate to come to a final vertical position by gravity.

I claim:

1. In a device of the class described, the combination with a pendulum, the major mass of which consists of a permanent magnet, of a solenoid with which, when energized, the permanent magnet reacts to deflect the pendulum, a contact piece with which the permanent magnet makes electric contact when the pendulum is deflected in one direction, a second contact piece with which the permanent magnet makes electric contact when the pendulum is deflected in the opposite direction, an independent circuit which includes the solenoid for deflecting the pendulum, a second independent circuit which is closed by contact between the permanent magnet and the first contact piece, said second circuit including the permanent magnet, the solenoid and the first contact piece, the purpose of said second circuit through the solenoid being to independently energize the solenoid to react with the permanent magnet to increase the contact pressure between the permanent magnet and the contact piece, and a third independent circuit which is closed by contact between the permanent magnet and the second contact piece, said third circuit including the permanent magnet, the solenoid and the second contact piece, the purpose of said third circuit through the solenoid being to independently energize the solenoid to react with the permanent magnet to increase the contact pressure between the permanent magnet and the second contact piece.

2. In a device of the class described, the combination with a pendulum, the major mass of which consists of a permanent magnet, of a solenoid with which, when energized, the permanent magnet reacts to deflect the pendulum, a contact piece with which the permanent magnet makes electric

contact when the pendulum is deflected in one direction, a second contact piece with which the permanent magnet makes electric contact when the pendulum is deflected in the opposite direction, an independent circuit which includes the solenoid for deflecting the pendulum, a second independent circuit which is closed by contact between the permanent magnet and the first contact piece, said second circuit including the solenoid for reacting with the permanent magnet to increase the contact pressure between the permanent magnet and the contact piece; a third independent circuit which is closed by contact between the permanent magnet and the second contact piece, said third circuit including the solenoid for reacting with the permanent magnet to increase the contact pressure between the permanent magnet and the second contact piece, means controlled by the second circuit for deenergizing the solenoid, and a second means for deenergizing the solenoid, said second means being controlled by the third circuit.

3. In a device of the class described, the combination with a stationary coil, of a pendulum which is capable of reaction with the coil to move the pendulum from its normal position when the coil is energized, a circuit for energizing the coil to move the pendulum, a contact piece with which the pendulum makes electric contact when the coil is energized by the circuit, an electrical means which, when energized, closes a switch, a second electrical means which, when energized, opens a second switch, a second circuit for energizing the first electrical means, which circuit is closed by contact between the pendulum and the contact piece, said second circuit including the coil, the second switch, and the first electrical means, and a third circuit for energizing the second electrical means, said third circuit including the first switch and the second electrical means.

4. In a device of the class described, the combination with a stationary solenoid, of a pendulum which is capable of reaction with the solenoid to move the pendulum from its normal position when the solenoid is energized, a circuit for energizing the solenoid to move the pendulum, a contact piece with which the pendulum makes electric contact when the solenoid is energized by the circuit, an electrical means which, when energized, closes a switch, a second electrical means which, when energized, simultaneously opens a second switch and closes a third switch, a second circuit for simultaneously energizing both the solenoid and the first electrical means and which is closed by contact between the contact piece and the pendulum, said circuit including the solenoid, the second switch, and the first electrical means, a third circuit for energizing the second electrical means, which circuit includes the first switch and the second electrical means, and a fourth circuit for energizing the second electrical means, said fourth circuit including the second electrical means and the third switch.

5. In a device of the class described, the combination with a pendulum, of a contact piece with which the pendulum, when forced out of its normal position, makes electric contact to close a circuit through an electrical means, a second electrical means which, when energized, operates a switch to open the circuit, a second switch actuated by the first electrical means which second switch, when the first electrical means is energized, closes a second circuit through the second electrical means, a third switch actuated by the

second electrical means which third switch, when the second electrical means is energized, closes a holding circuit through said second electrical means, and a third electrical means included in the first circuit which third electrical means, when energized, reacts with the pendulum to force it against the contact piece.

6. In a device of the class described, the combination with a pendulum, of a contact piece with which the pendulum, when forced out of its normal position, makes electric contact to close a circuit through an electrical means, a second electrical means which, when energized, operates a switch to open the circuit, a second switch actuated by the first electrical means which switch, when the first electrical means is energized, closes a second circuit through the second electrical means, a third switch actuated by the second electrical means for closing a holding circuit through said second electrical means, a third electrical means included in the first circuit which third electrical means, when energized, reacts with the pendulum to force it against the contact piece, an independent circuit which also includes the third electrical means, and a source of electrical energy in the independent circuit for energizing said third electrical means to react with the pendulum to force the pendulum out of its normal position.

7. In a device of the class described, the combination with a permanent magnet suspended in the form of a pendulum, of a contact piece with which the permanent magnet, when deflected counter-clockwise from its normal position, makes electric contact to close a circuit through an electrical means, a second electrical means which, when energized, operates a switch to open the circuit, a second switch actuated by the first electrical means which switch, when the first electrical means is energized, closes a second circuit through the second electrical means, a third switch actuated by the second electrical means for closing a holding circuit through the second electrical means when said electrical means is energized, a second contact piece with which the permanent magnet, when deflected clockwise from its normal position, makes electric contact to close a third circuit through a third electrical means, a fourth switch actuated by the third electrical means, said fourth switch opening the holding circuit when the third electrical means is energized, a fifth switch for opening the third circuit, said fifth switch being actuated by the second electrical means and opened thereby when said second electrical means is deenergized, a solenoid for reacting with the permanent magnet when said solenoid is energized, said solenoid being included in both the first and third circuits, a battery in the first circuit of the proper polarity to force the permanent magnet counter-clockwise, a second battery in the third circuit of the proper polarity to force the permanent magnet clockwise, and an independent circuit which includes the solenoid to deflect the permanent magnet from its normal position.

8. In a device of the class described, the combination with a pendulum, of a permanent magnet carried by the pendulum, a contact piece with which the pendulum makes electric contact when deflected clockwise from its normal position, a second contact piece with which the pendulum makes electric contact when deflected counter-clockwise from its normal position, a solenoid which, when energized, reacts with the

magnet to exert a force on the pendulum, to deflect it from its normal position, a circuit which includes the pendulum, the first contact piece and the solenoid, a second circuit which includes the pendulum, the second contact piece and the solenoid, a battery in the first circuit for energizing the solenoid to force the pendulum clockwise, a second battery in the second circuit for energizing the solenoid to force the pendulum counter-clockwise, a switch in the first circuit the opening of which switch is controlled by the first circuit and the closing of which is controlled by the second circuit, a second switch in the second circuit the opening of which second switch is controlled by the second circuit and the closing of which is controlled by the first circuit, and a third circuit which includes the solenoid for deflecting the pendulum out of its normal position and against the first or second contact piece to respectively close the first or second circuit.

9. In a device of the class described, the combination with a galvanometer consisting of a movable member and a coil which reacts with a permanent magnet to deflect the member, of a switch which is closed by the coil when the coil is energized, an electrical means, a circuit through the coil and the electrical means which circuit is closed by the switch, a second switch operated by the electrical means, when energized, to close a second circuit through a second electrical means, a third switch operated by the second electrical means, when energized, to open the first circuit, a fourth switch operated by the second electrical means, when energized, for closing a holding circuit through the second electrical means, and an independent circuit through the coil for actuating the first switch.

10. In a device of the class described, the combination with a galvanometer consisting of a movable member and a coil which when energized reacts with a permanent magnet to deflect the member, of a switch which is closed by the coil when energized in one direction, an electro-magnet, a circuit which is closed by the switch, said circuit including the coil and the electro-magnet in series, a second switch operated by the electro-magnet, when energized, to close a second circuit through a second electro-magnet, a third switch operated by the second electro-magnet, when energized, to open the first circuit, a fourth switch operated by the second electro-magnet, when energized, to close a holding circuit through the second electro-magnet, a fifth switch which is closed by the coil when energized in the opposite direction, a third electro-magnet, a sixth switch which is closed by the second electro-magnet when energized, a fourth circuit which is closed by the fifth switch said fourth circuit including the coil, the sixth switch and the third electro-magnet in series, a seventh switch operated by the third electro-magnet, when energized, to open the holding circuit thereby deenergizing the second electro-magnet to open the sixth switch and again close the third switch, a battery in the first circuit of the proper polarity to energize the coil in the proper direction to close the first switch, a second battery in the fourth circuit of the proper polarity to energize the coil in the proper direction to close the fifth switch, and independent means for energizing coil.

11. In a device of the class described, the combination with a galvanometer consisting of a movable member and a coil which, when energized,

reacts with a permanent magnet to deflect the member, of a switch which is closed by the coil when energized in one direction, an electro-magnet, a circuit which is closed by the switch, said 5 circuit including the coil and the electro-magnet in series, a second switch operated by the electro-magnet, when energized, to close a second circuit through a second electro-magnet, a third switch operated by the second electro-magnet, 10 when energized, to open the first circuit, a fourth switch operated by the second electro-magnet, when energized, to close a holding circuit through the second electro-magnet, a fifth switch which is closed by the coil when energized in the opposite direction, a third electro-magnet, a sixth switch which is closed by the second electro-magnet when energized, a fourth circuit which is 15 closed by the fifth switch said fourth circuit including the coil, the sixth switch and the third electro-magnet in series, a seventh switch operated by the third electro-magnet, when energized, to open the holding circuit thereby deenergizing the second electro-magnet to open the sixth switch and again close the third switch, a 20 battery in the first circuit of the proper polarity to energize the coil in the proper direction to close the first switch, a second battery in the fourth circuit of the proper polarity to energize the coil in the proper direction to close the fifth switch, a thermo-couple for energizing the coil, 25 an independent circuit which includes the coil and the couple, and an adjustable potentiometer in the independent circuit for balancing the electro-motive force of the couple for any given temperature of the couple.

12. In a device of the class described, the combination with a pendulum, of a permanent magnet which forms part of the pendulum, a solenoid with which the magnet reacts, when the solenoid is energized, to deflect the pendulum, a circuit which includes the solenoid to thus deflect the pendulum in a given direction against a fixed contact piece, means for increasing the contact pressure between the pendulum and the contact piece, said means consisting of an independent circuit of given polarity which includes the solenoid and is closed by contact between the pendulum and the contact piece, a second contact piece with which the pendulum, when deflected in the opposite direction makes electrical contact and means for increasing the contact pressure between the pendulum and the second contact piece, said means consisting of a second independent circuit of opposite polarity which includes the solenoid and is closed by contact between the pendulum and the second contact piece.

13. In a device of the class described, the combination with a solenoid included in each of three different circuits, of a pendulum, a permanent 60 magnet fastened to and forming part of the pendulum, said permanent magnet reacting with the solenoid to deflect the pendulum when the solenoid is energized; a thermo-couple and a potentiometer for balancing the electro-motive force of the couple, said thermo-couple and potentiometer being included in the first circuit for energizing the solenoid to deflect the pendulum, an electro-magnet, a switch which is opened by a second electro-magnet when energized, and a second switch which is closed by the pendulum when the solenoid is energized in one direction, said first electro-magnet and said first and second switches being included with the solenoid in the second circuit, a third electro-magnet, a 65 third switch which is closed by the second elec-

tro-magnet when energized, and a fourth switch which is closed by the pendulum when the solenoid is energized in the opposite direction, said third and fourth switches and the third electro-magnet being included with the solenoid in the 5 third circuit, a fifth switch which is closed by the first electro-magnet, when energized, for closing a fourth circuit through the second electro-magnet, a sixth switch actuated by the second electro-magnet for closing a holding circuit 10 through said second electro-magnet when the second electro-magnet is energized, a seventh switch which is opened by the third electro-magnet, when energized, for opening the holding circuit, and an eighth switch actuated by the 15 second electro-magnet for opening and closing a fifth circuit.

14. In a device of the class described, the combination with a relay, of a first, second and third switch each of which is closed by the relay when energized and opened by the relay when deenergized, a fourth switch which is opened by the relay when energized and closed by the relay when deenergized, means actuated by the relay for closing the first switch before the fourth 20 switch is opened, a second relay, a fifth switch which is closed by the second relay when energized and opened by said relay when deenergized, a third relay, a sixth switch which is opened by the third relay when energized and closed by said 25 relay when deenergized, a pendulum, a permanent magnet which forms part of the pendulum, a solenoid which when energized reacts with the magnet to force the pendulum from its normal position, a seventh switch which is closed by 30 the pendulum when forced in a counter-clockwise direction, an eighth switch which is closed by the pendulum when forced in a clockwise direction, a battery of given polarity, a circuit which includes the battery, the solenoid, the 35 pendulum, the seventh switch, the second relay, and the fourth switch, a second battery of opposite polarity, a second circuit which includes the second battery, the solenoid, the pendulum, the eighth switch, the second switch, and the third 40 relay, a third circuit which includes the fifth switch, the first relay and the sixth switch, a fourth circuit which includes the first switch, the first relay, and the sixth switch, a thermo-couple for energizing the solenoid to deflect the 45 pendulum, an adjustable potentiometer for balancing the electro-motive force of the couple, and a fifth circuit which includes the couple, the potentiometer and the solenoid.

15. In a device of the class described, the combination with a pendulum, of a permanent magnet fastened to the pendulum, electro-magnetic means for reacting with the permanent magnet to deflect the pendulum, an electric circuit for energizing the electro-magnetic means to deflect the pendulum, a contact piece with which the pendulum makes electric contact when deflected, a second circuit through the electro-magnetic means which second circuit is closed by said electric contact for independently energizing the electro-magnetic means to force the pendulum tightly against the contact piece, and a relay actuated by the second circuit to operate a second relay which second relay opens the second circuit through a switch included in said 60 second circuit.

16. In a device of the class described, the combination with a pendulum of a permanent magnet fastened to the pendulum, electro-magnetic means for reacting with the permanent magnet 65

to deflect the pendulum in a counter-clockwise or clockwise direction depending upon whether the current flow through the electro-magnetic means is in one direction or the other, a contact piece with which the pendulum makes electric contact when deflected counter-clockwise, a second contact piece with which the pendulum makes electric contact when deflected clockwise, a circuit through the electro-magnetic means which is closed by contact between the pendulum and the first contact piece and which circuit includes a battery of given polarity, a relay actuated by the circuit to operate a second relay which second relay when energized opens a switch to open the circuit, a second switch which is closed by the second relay to close a second or holding circuit through the second relay, a third circuit through the electro-magnetic means, which circuit is closed by contact between the pendulum and the second contact piece and which circuit includes a second battery of opposite polarity, a third relay actuated by the third circuit to open the holding circuit through the second relay, a third switch, included in the third circuit, which switch is opened by the second relay when deenergized, and an independent circuit through the electro-magnetic means for deflecting the pendulum against one or the other of the contact pieces.

17. In a device of the class described, the combination with a pendulum, the major mass of which consists of a permanent magnet, of an electro-magnet located in a fixed position which, when energized, reacts with the permanent magnet to deflect the pendulum, a contact piece with which the permanent magnet makes electrical contact when the pendulum is deflected, a circuit which includes the electro-magnet and a source of electrical energy for deflecting the pendulum against the contact piece, a second circuit which is independent of the first circuit and which includes the electro-magnet and an independent source of electrical energy for forcing the permanent magnet against the contact piece, said second circuit being closed by contact between the permanent magnet and the contact piece, and electrical means in the second circuit for simultaneously closing a third circuit and opening the second circuit.

18. In a device of the class described, the com-

bination with a pendulum, the major mass of which consists of a permanent magnet, of an electro-magnet which, when energized, reacts with the permanent magnet to deflect the pendulum, a contact piece with which the permanent magnet makes electrical contact when the pendulum is deflected, a circuit which includes the electro-magnet and a source of electrical energy for deflecting the pendulum against the contact piece, a second circuit which is independent of the first circuit and which is closed by contact between the permanent magnet and the contact piece, said second circuit including the electro-magnet and a battery which is independent of said source of electrical energy, said battery energizing the electro-magnet to react with the permanent magnet and the contact piece, and electrical means in the second circuit for cutting out the energy from the battery to the electro-magnet and simultaneously closing a third circuit.

19. In a device of the class described, the combination with a suspended permanent magnet, of a fixed coil which, when energized by a source of electrical energy through an independent circuit, reacts with the magnet to deflect the magnet from its normal position, and means for closing a second electric circuit through the coil, said means being actuated by the force of reaction between the magnet and the coil when said coil is momentarily energized by a second and independent source of electrical energy substantially as described.

20. In a device of the class described, the combination with a pendulum, of a permanent magnet which forms part of the pendulum, a solenoid with which the magnet reacts, when the solenoid is energized to deflect the pendulum, a circuit which includes the solenoid and a source of electrical energy to deflect the pendulum against a contact piece, means for increasing the contact pressure between the pendulum and the contact piece, said means consisting of a second source of electrical energy of the proper polarity in an independent circuit which includes the solenoid and is closed by the initial contact between the pendulum and the contact piece, and electrical means controlled by the second circuit for cutting out the second source of electrical energy.

FRITZ FREDERICK UEHLING. 50
